PAPER COLORING DEVICE

Filed July 26, 1926

UNITED STATES PATENT OFFICE.

KARL WILLE, OF SOMERVILLE, NEW JERSEY, AND WILLIAM TIEKE, OF ASTORIA,
NEW YORK, SAID TIEKE ASSIGNOR TO SAID WILLE.

PAPER-COLORING DEVICE.

Application filed July 26, 1926. Serial No. 124,994.

This invention relates generally to improvements in paper coloring devices used to color paper so as to render same suitable for coverings, the invention having more 5 particular reference to a novel type of paper coloring device which will repeatedly produce irregular designs.

The invention has for an object the provision of an improved paper coloring device 10 embodying certain novel features which will render the said device more efficient and practical.

For further comprehension of the invention, and of the objects and advantages 15 thereof, reference will be had to the following description and accompanying drawing, and to the appended claims in which the various novel features of the invention are more particularly set forth.

20 Fig. 1 of the drawing is a top plan view of the color spreading device.

Fig. 2 is a side elevational view, partly in section.

Fig. 3 is an enlarged fragmentary sectional view taken on the line 3—3 of Fig. 1.

Fig. 4 is a transverse sectional view taken on the line 4—4 of Fig. 3.

Fig. 5 is a fragmentary longitudinal sectional view taken on the line 5—5 of Fig. 3.

30 Fig. 6 is a schematic drawing of a paper coloring device embodying our improved spreading device.

Fig. 7 is an enlarged sectional detail view 35 of a color spreading bushing adapted for use in our improved device.

Referring in particular to Fig. 6, of the accompanying drawing, the container 10, adapted to hold water 11, has rotatively mounted therein, a roller 12, partly submerged in the water 11, and in contact with a roller brush 13 rotatively mounted in the container 10, above the water 11, the roller brush 13 is also in contact with the outer surface of the paper 14, which is wound 40 on a roller 15, rotatively mounted in the frame work 16, which also supports the container 10. The paper 14 is extended over the roller 17, rotatively mounted in the frame work 16, and is rewound on a roller, 45 not shown in the drawing, the latter named roller being driven or rotated by any suitable, convenient means, such as an electric motor, or any convenient prime mover. The paper 14, to be colored by our improved 50 color spreading device, is moistened by the

roller brush 13, as is obvious by the foregoing description. The above described construction is such as generally used for paper coloring devices, and are usually provided with an endless flexible member 18, of rubber, felt, or the like extended over the roller 17, underneath the paper 14, and is extended over a roller 19, rotatively mounted in an arm 20, pivoted, as at 21, to the frame work 16, and having a handle 17, and provided 60 with any suitable means of holding the roller 19 in any desired position, such as a pin 22, adapted to engage in any desired one of the apertures 23, located in the segment member 24 attached to the frame work 16. 65 The latter described construction being such as will permit the flexible member 18 to prevent the paper 14 from being torn or injured, due to the moistening of the said paper, and which will permit the flexible member 18 to be tensioned as may be required. 70

It will be understood that we do not necessarily limit the use of our invention 80 to the particular type of paper coloring device as above described, but to all classes of paper coloring devices, such as generally used.

As here embodied our improved color spreading device comprises a plurality of separate compartments 25, of box like construction, positioned side by side, and placed crosswise of the above mentioned paper 14, over the said paper in close proximity to the roller 17, and supported by the said 90 frame work 16. The compartments 25, are adapted to hold the color, paint or the like, to be spread or dripped on the paper 14, and are provided with covers 26, removably attached thereto, as at 27, by bolts, screws, 95 or the like.

The valves 28 consist of tapered cylindrical members 29, positioned in similar shaped apertures formed in the base element 30, of the compartments 25, and are provided with threaded extremities, adapted to receive nuts 31, as a means of properly tightening the valves 28, so as to prevent leakage of the color in the compartments 25, 100 when the said valves are in a closed position. The tapered cylindrical members 29, are provided with transverse apertures 32, registering with apertures 33, formed in the slid able member 34, and with apertures 35, formed in the color spreading bushings 110

36 positioned in the base element 30 of the compartments 25, when the said valves 28 are in an open position, so as to permit the color in the compartments 25 to be spread 5 or dripped on the paper 14, by means of turning or rotating the said valves by the handles 37 depending therefrom.

The slideable member 34 is slidably positioned in an elongated slot 38 formed in the 10 base element 30 of the compartments 25, and is held in position therein, by straps 40, removably attached to the base element 30, as at 41, by bolts, screws, or the like. The slideable members 34 are extended through the 15 ends 42 of the compartments 25, and are provided with adjustable members 43, such as studs, or the like, threadedly attached thereto, to which are pivotally attached, as at 44, cranks 45, pivotally attached, as at 46, to 20 supports 47, slidably engaged in a radial slot 48 formed in the disk 49, the supports 47 are provided with nuts 50, threadedly attached thereto, as a means of holding the supports 47 in any desired relative position in the radial slots 48. The disks 49, are rotatively mounted in supports 51, and have attached thereto a sprocket 51', the sprocket chain 52 is extended over the sprocket 51' and over the sprocket 53, rotatively mounted in the 25 supports 54, attached to the ends 42 of the compartment 25, as at 55.

The above described construction being such as will permit the slideable member 34 to be oscillated or slid back and forth, so as to regulate the spreading or dripping of the 30 said color on the paper 14, and to simultaneously control the said dripping, so as to produce repeated irregular designs.

The supports 51 are slidably mounted on 40 the brackets 56, attached to the ends 42 of the compartments 25, and are held in any desired relative position by the adjustable member 57, rotatively mounted in the bracket 56, and threadedly attached to the support 45 51, as at 58, and provided with hand wheels 59. The above described construction being such as will permit the slideable members 34 to be further controlled, as may be desired, to vary the dripping of the said color. Suitable graduations 60, may be placed in the bracket 56, as a means of determining the 50 setting of the slideable members 34.

It being understood that the compartments 55 25, may be held in any desired position, so as to permit the above mentioned setting of the slideable members 34, by means of the adjustable members 61, rotatively mounted in the brackets 62 attached to the frame work 16, as at 63, threadedly attached to the compartments 25, as at 64.

Referring in particular to Fig. 7 of the accompanying drawing, the color spreading bushings 36, may be provided with tapered cavities 65, terminating in apertures 66, which may be of different sizes or diameters,

so as to control or vary the dripping of the color.

It is obvious that we have provided a device which will regulate the dripping of the color to be spread on paper, so as to produce 70 repeated irregular designs, in different colors.

While we have above described the preferred form, construction, and arrangement of the several elements employed, it will be understood that the device is, nevertheless, 75 susceptible of considerable modification therein, and we therefore reserve the privilege of resorting to all such changes as may be fairly embodied within the spirit and scope of the invention as claimed. 80

Having thus described our invention, what we claim as new and desire to protect by Letters Patent of the United States is as follows:

1. In a paper coloring device of the class 85 described, a color spreading device comprising a plurality of separate compartments adapted to hold color, valves positioned in the base elements of the said compartments, as a means of regulating the dripping of the 90 said color on paper, so as to produce irregular designs, slideable members positioned in elongated slots formed in the said base elements of the said compartments, adjustable members attached thereto, and pivotally attached to cranks, said cranks pivotally attached to supports slidably engaged in radial slots formed in disks, said supports in any relative position in the said radial slots, said disks rotatively mounted in second supports, sprockets attached thereto, a sprocket chain extended over the said sprocket wheel, as a means of oscillating the said slideable 95 members so as to regulate the dripping of the said color in the said paper. 100

2. In a paper coloring device of the class 105 described, a plurality of separate containers for coloring matter having spaced openings in the bottom thereof, slidably mounted members disposed in grooves in the bottom of said container having openings therein adapted to register with the openings in said bottom, and means for reciprocating said slideable members for periodically moving the holes therein into and out of registration with the holes in said bottom for regulating the flow of coloring material from said containers. 110

3. In a paper coloring device of the class 115 120 described, a plurality of separate containers for holding coloring material having spaced openings in the bottom thereof, valves mounted in said openings for regulating the flow of coloring therethrough, slideable members mounted in a groove in the bottom of said containers having openings therein adapted to register with the openings of the bottoms of said containers, and reciprocating mechanism comprising rotatively mounted discs adjustably connected with 125 130

- said slidable members for reciprocating the latter to position the holes therein alternately in and out of registration with the openings in said bottoms for regulating dripping 5 of coloring material therethrough, said reciprocating mechanism being adjustable for varying the arrangement of said slidable members for changing the sequence of the dripping operations.
- 10 4. In a paper coloring device of the class described, a plurality of separate containers for holding coloring material having spaced openings in the bottom thereof, valves mounted in said openings for regulating the 15 flow of coloring therethrough, slidable members mounted in a groove in the bottom of said containers having openings therein adapted to register with the openings of the bottoms of said containers, discs having radial grooves therein rotatively mounted on said containers, blocks adjustably mounted in said grooves, and connecting links pivotally attached at one end to said adjustable blocks and at the other end to said slidable 20 members for reciprocating the latter to bring the openings therein into and out of 25 registration with the openings in the bottoms of said containers for regulating the flow of coloring material therethrough, said blocks being adjustable for changing the relative periodic opening and closing of the openings in the bottoms of said containers to vary the design formed by dripping of coloring material therethrough.
- 30 5. In a coloring device of the class described, a plurality of containers for coloring material having openings in the bottoms thereof, slidable members having openings therein slidably mounted in grooves in the bottoms of said containers, and actuating 35 mechanism for reciprocating said slidable members to position the openings in the latter alternately into and out of registration with the openings in said bottoms for regulating dripping of coloring material therethrough to producing a repeated irregular 40 design.
- 45 In testimony whereof we have affixed our signatures.

KARL WILLE.
WILLIAM TIEKE.
